UNITED STATES PATENT OFFICE.

CLARENCE R. WALTER, OF SAN FRANCISCO, CALIFORNIA.

SHIPPING OR TRAVELING CASE.

SPECIFICATION forming part of Letters Patent No. 728,524, dated May 19, 1903.

Application filed May 17, 1902. Serial No. 107,854. (No model.)

To all whom it may concern:

Be it known that I, CLARENCE R. WALTER, a citizen of the United States of America, and a resident of the city and county of San Francisco, in the State of California, have invented certain new and useful Improvements in Shipping or Traveling Cases, of which the following is a specification.

My invention particularly relates to trunks and chests such as are used for packing cloth, merchandise, personal effects, &c.; and it has for its object to produce such an article in which the contents are yieldingly held in position and wherein the top of the goods or contents is automatically kept in the upper part of the case, so as to facilitate the packing or filling and the emptying thereof.

The invention consists in the improved construction and novel arrangement of parts of such a case, trunk, or receptacle, as will be hereinafter more fully set forth.

In the accompanying drawings, in which the same reference-numerals indicate corresponding parts in each of the views where they occur, Figure 1 is a broken end elevation of a trunk embodying one form of my invention. Fig. 2 is a top view of the same, the lid or cover being omitted. Fig. 3 is a transverse vertical sectional view of the trunk filled and closed. Fig. 4 is a similar view embodying a different form of my invention, the lid of the trunk being open and partly broken away. Fig. 5 is a broken end elevation showing another modification of my invention. Fig. 6 is a broken plan view of one end of the trunk as shown in Fig. 5. Fig. 7 is an enlarged perspective view of an inside corner of the trunk, showing details supplementary to Fig. 1. Fig. 8 is a top view, on a reduced scale, of the construction shown in Fig. 7. Fig. 9 is a broken elevation reproducing part of the trunk as represented at Fig. 4 with the tray thereof in inverted position. Fig. 10 is a perspective view of one form of tray that may be used in the form of trunk shown in Figs. 1, 2, and 3. Fig. 11 illustrates one method of forming the end of this tray. Fig. 12 shows a reinforcing-piece applied thereto. Fig. 13 is a plan view of the blank from which this reinforcing-piece is formed. Fig. 14 is a perspective of a collapsi-

ble tray adapted for use with the trunk, particularly when made as in Figs. 4 and 9. Figs. 15 and 16 are plans of this collapsible tray, the former showing it spread out and the latter folded; and Fig. 17 is a detail view.

Referring more particularly to the said drawings, the numeral 1 indicates a trunk or case, which may be of any suitable dimensions and constructed in any desired manner. A lid 2 is hinged or otherwise secured to the top of the trunk-body and, as usual, is adapted to be closed and locked to prevent the escape of the contents of the trunk. 65

Yieldingly held within the trunk 1 at any desired distance from the top is a platform 3, upon which the contents of the trunk are placed and preferably held by means of retaining devices, as straps 4 and 5. These straps are arranged in pairs and secured at one of their ends to the front and rear walls of the trunk, respectively, and the free ends of each pair of said straps are adapted to be detachably fastened together, as by a buckle 75 6. The platform 3 can be made in any desired manner, although I prefer to construct it from longitudinal and transverse slats (best seen in Fig. 2) as giving the required strength with the least weight. The aforesaid platform is of such size or dimensions as to fit snugly within the body of the trunk 1 without excessive lateral play, but may be moved vertically. The yielding support for this platform may be located above or below it and may occupy 80 space within the body of the trunk or be embedded or located within the trunk-wall. When located above the platform, I prefer to construct the said support of coiled springs 7 and place them one at each corner, where 90 they will hold the platform against tipping and at the same time will take up but little room. The springs 7 may be secured to the corners of the platform at their lower ends by means of staples or eyebolts 8 and have their 95 upper ends permanently or detachably connected to the top of the trunk-body, as by means of cleats or strips of metal 9, the ends of which rest upon the trunk-walls. The upper end of each spring 7 is preferably formed 100 into a stirrup or loop 10, through which the corresponding cleat is passed before its ends

are secured to the trunk-body. When it is desired to support the platform 3 from below, I prefer to make the springs in the form of an expanded or open convolute spiral, as 5 shown at 11, Fig. 4, so that when the platform is forced down by its load the coils will fit within each other, and thus take up the least possible room. In this manner the space between the trunk-walls above the platform 10 will be entirely free and unobstructed and a little more room afforded than with the suspension or tension springs 7.

Instead of locating the supporting-springs so as to take up any of the room of the trunk, 15 as above described, they may be located within recesses 12, Figs. 5 and 6, preferably at the ends. In this construction the springs are multiple, consisting in each instance of a series of flat and elliptical members connected 20 with one another in the form of lazy-tongs, as shown at 13, and each series may be attached to the trunk-body by means of a bolt 14 and to the platform by a metal strip 15, secured to and projecting laterally from the lower 25 leaf of the bottom spring member. The recess 12 for each spring series extends from near the top of the trunk-body to the bottom, so as to admit of the expansion of the springs to the utmost when the platform is loaded to 30 its fullest capacity and is forced down to the bottom of the trunk.

In using my improved case or trunk, as above described, the lid is opened and the straps 4 and 5 turned out of the way, the 35 straps 5 at the rear being held back from over the platform 3 by means of suitable retainers, as straps 16, secured to the interior of the lid and extending down into position to be engaged by the buckle 6. The goods or 40 other articles are then placed upon the platform 3, and after the platform has been loaded, partly or fully, as desired, its springs yielding as the weight thereon increases, the straps 4 and 5 are joined together over the load with 45 or without an interposed board 17, Fig. 3, and the trunk-lid is closed and fastened. By giving the aforesaid springs the proper tension the top of the bulk of material upon the platform 3 will always remain at about the same 50 distance relatively to the top of the trunk. This makes it much more convenient and easy to fill or empty my trunk than where no such provision is made, for the platform will sink as the load increases in filling and rise 55 in emptying the trunk. In this way the heavy and laborious task of lowering or lifting big rolls of cloth, such as are indicated by 18 in Fig. 3 or other ponderous commodities to or from the bottom of the trunk, is avoided. 60 My invention also saves time, as the articles being put in or taken out are always near the top, and therefore can readily be arranged in proper position when filling the trunk or taken hold of and removed in emptying it. It fur- 65 thermore admits of a partial trunkful being shipped as securely as though the trunk were entirely full, since the springs will always

hold the goods tightly between the straps 4 and 5 on top or the top board 17 and the platform beneath.

In Figs. 7 and 8 I have shown means for isolating the springs 7 that are employed in the form of my invention first above described and more particularly illustrated by Figs. 1, 2, and 3. These isolating means consist of 75 shields 19, one for each spring 7, and are designed to prevent the convolutions of the several springs or either of them from catching in or rubbing against the edges of certain classes of goods or articles as they are placed 80 in or taken out of the trunk. Each shield, as shown, is suitably curved and flanged for attachment to one corner of the trunk and the secure confinement therein of its respective spring, and each is further provided with 85 a vertical slot 20 for the passage therethrough of the suspending connection between this spring and the adjacent corner of the platform 3. The suspending connection in the present case is preferably a Y-shaped fastening 90 21, whose stem passes through the slot 20 and is attached to the lower end of the spring 7 and the branches of which are respectively secured to the meeting ends of the outermost slats of the platform 3 at the corresponding 95 corner. By these means the platform is left entirely free to move up and down, and there can be no possible contact or interference between its suspending springs and the load it carries.

To render my trunk available for stowing or shipping smaller articles than can be secured by the aforesaid straps and platform, I employ in connection therewith one or more shallow boxes or trays, either with or without 105 covers. In Figs. 10, 11, and 12 I have illustrated a very desirable form of such a tray, (therein marked 22,) which tray is best adapted for use with the form of my invention in which the platform 3 is supported at the corners by the springs 7. In this tray 22 the corners are preferably cut off, as suggested by the dotted line 23 in Fig. 11, and a strengthening-plate 24 is secured to the walls and bottom, as shown in Figs. 10 and 12. The 110 24 is preferably formed from a T-shaped blank, (detailed in Fig. 13,) the several members of which are bent at suitable angles and rigidly secured to the walls and bottom, respectively, of the tray. In using 115 such trays they are filled with the articles which they are to contain, and where there is a lid, as 25 in Fig. 10, it is closed down, and the trays are placed one on top of another upon the platform 3, the weight of each tray 120 125 affecting the springs and causing them to operate in the same manner as the more bulky articles hereinbefore mentioned.

Figs. 14, 15, and 16 show another very convenient form of tray which can be used with 130 any trunk, but is best employed in combination with the spring-pressed platform illustrated in Figs. 4 and 9. This tray is foldable and comprises parallel sides 26 27, joined by

centrally-divided ends 28 29, which sides and ends are respectively connected one with the other by longitudinal tapes 30 and transverse tapes 31, tacked on or otherwise secured to their bottom edges, as represented in perspective and in plan in Figs. 14 and 15. Each end 28 29 is composed of two members of equal length, which are attached one to the other by means of an external hinge 32 and similarly connected each to its adjoining side 26 27 by an internal hinge 33, so that when the tray formed thereby is unfolded the two sides and two ends will constitute, with their interconnecting bottom tapes 30 31, a rectangular receptacle fitting the inside of the trunk-body and adapted to receive various articles of wearing-apparel or dry goods of various sorts, and when the tray is empty the ends can be pushed inward and the sides drawn toward each other—that is, collapsed and folded, as suggested at Fig. 16. While thus folding the tray, the tapes are gathered and lodged between the closed sides and ends, as will be understood. In order to keep these sides and ends sufficiently rigid and their tapes suitably stretched between them whenever the tray is opened for use, I provide a hook 34 on one member of each end and a catch 35 for this hook on the companion member thereof. The hook 34 and catch 35 for each end are placed on the inside of the tray, so as to act oppositely to the external hinge 32 in each instance. To fold the tray, the hook 34 is simply pulled off its catch 35, and the tray then readily collapses. In using this form of collapsible tray I find it convenient to place first an ordinary tray, as 36, on the platform 3, as shown in Fig. 4, and after filling the latter tray I superimpose thereon the desired number of foldable trays or as many as the trunk is calculated to hold, the platform descending, as before explained, as the several trays are deposited in the trunk. After emptying the trunk if it be desired to keep it empty I invert the tray 36, as indicated in Fig. 9, so that its sides will hang down below the sides or edges of the spring-raised platform 3, and having collapsed the other trays I place them, carefully folded, upon the bottom of the said tray 36, their collapsibility enabling me to store them all within the upper part of the trunk 1 in the restricted space comprised between its lid 2 and its said spring-raised platform 3.

55 Although I have shown and described what I consider the preferred forms of my improved shipping or traveling case and illustrated the same in the shape of an ordinary trunk, yet I do not wish to be understood as limiting my invention to the exact construction herein set forth, as it is evident that other forms may be adopted, and I reserve the right to make such changes and alterations as will come within the scope of my said invention. For instance, the body of the receptacle may be in the shape of a box or even be made cylindrical instead of in the form of

a trunk, and the coil-springs may be secured to the body of the trunk by other means than the cleats, as a hook or clasp, and the straps 70 at the back can be held out of the way by a hook or projection in the trunk-lid instead of a strap, and instead of elliptical springs within the recesses at the ends of the trunk other forms of springs could be used or ordinary 75 lazy-tongs may be substituted for them with or without springs for holding the tongs in their open position.

What I claim, and desire to secure by Letters Patent of the United States, is— 80

1. In a shipping or traveling case, a hollow body provided with a lid, a vertically-yielding platform in the body, straps at the front and back of the body secured directly thereto, and arranged to be connected together 85 above the platform, and means in the lid at the rear portion thereof for temporarily holding the back strap out of the way; substantially as described.

2. In a shipping or traveling case, a hollow 90 body provided with a hinged lid, a vertically-yielding platform in the body, pairs of straps secured to the sides of the case and adapted to be connected together above the platform, the rear strap of each pair being provided 95 with a buckle, and straps in the lid the free end of each of which is adapted to engage with the buckle of its respective strap on the rear wall of the case and hold said strap out of the way, substantially as described. 100

3. In a shipping or traveling case, a hollow body, a vertically-movable platform therein, and oppositely-disposed springs each secured at one end against movement to the top of the body and at its opposite end to the platform; substantially as described. 105

4. In a shipping or traveling case, a hollow body, a vertically-movable platform therein, a coiled spring secured to each corner of the platform, the upper end of which spring is 110 provided with a loop, and a cleat through each loop, the ends of which cleats are secured to the top of the body, substantially as described.

5. In a shipping or traveling case, a hollow 115 body, a platform vertically movable therein, springs located by the platform, suitably-apertured shields for the springs, and connections passing through the shields for supporting the platform from the springs, substantially as described. 120

6. In a shipping or traveling case, a hollow body, a platform movable vertically therein, a coiled spring placed at each corner of the platform, a slotted shield for each spring, 125 and fastenings interconnecting the platform and springs through the slotted shields, substantially as described.

7. In a shipping or traveling case, a hollow body provided with a pocket, a vertically-movable platform in the body, and a spring in said pocket secured against movement at one end and having its opposite end secured to the platform; substantially as described. 130

8. In a shipping or traveling case, a hollow body, a vertically-movable platform therein, springs arranged at the corners of the body secured to the platform and to the body, and 5 a tray adapted to be carried by the platform, each corner of which is cut off to prevent engagement with the springs; substantially as described.

9. In a shipping or traveling case, a hollow 10 body, a vertically-movable platform therein, springs arranged at the corners of the body and secured to the platform and to the body, a tray adapted to be carried by the platform,

each corner of the tray being cut off, and a T-shaped strengthening-plate for each corner, the members of which plate are bent at suitable angles and secured to the walls and bottom respectively of the tray; substantially as described. 15

In testimony whereof I have signed my 20 name to this specification in the presence of two subscribing witnesses.
